CLAIM

I claim the ornamental design for a tool for a cleaning appliance, as shown and described.

DESCRIPTION

FIG. 1 is a perspective view of a tool for a cleaning appliance showing my new design;

FIG. 2 is a top view thereof;

FIG. 3 is a bottom view thereof;

FIG. 4 is a side view thereof;

FIG. 5 is a side view of the opposite side of FIG. 4;

FIG. 6 is a front end view thereof; and,

FIG. 7 is a rear view thereof.
